UNITED STATES PATENT OFFICE.

GEORGE W. CONRAD, OF ST. BENEDICT, PENNSYLVANIA, ASSIGNOR TO REMBRANDT PEALE, OF NEW YORK, N. Y.

ELECTRICAL BOND.

Application filed April 16, 1920. Serial No. 374,434.

To all whom it may concern:

Be it known that I, GEORGE W. CONRAD, a citizen of the United States, residing in St. Benedict, in the county of Cambria and State of Pennsylvania, have invented certain new and useful Improvements in Electrical Bonds, of which the following is a specification.

The invention relates to track equipment devices for electrical traction, and more particularly to electrical railway track bonds, although in certain of its aspects the invention is applicable to other uses in electrical conduction equipment.

Objects and advantages of the invention will be set forth in part hereinafter and in part will be obvious herefrom, or may be learned by practice with the invention; the same being realized and attained by and through the instrumentalities pointed out in the appended claims.

The invention consists in the novel parts, constructions, arrangements, combinations and improvements herein shown and described.

The accompanying drawings referred to herein and constituting a part hereof, illustrate one embodiment of the invention, and together with the description serve to explain the principles of the invention.

Of the drawings:

Fig. 1 is a horizontal section through two abutting rail ends, showing the bond;

Fig. 2 is a vertical section through the rail, showing most of the bond connections in elevation in position in the rail;

Fig. 3 is a detail of the bolt which passes through the rail;

Fig. 4 is a perspective detail of the bolt of Fig. 3 showing the bond wire in position in the bolt;

Fig. 5 is a detail of one side of the contact bearing block;

Fig. 6 is a detail of the other side of the block shown in Fig. 5;

Fig. 7 is an edge detail of the block shown in Figs. 5 and 6;

Fig. 8 is a side detail of the bushing which surrounds the bolt within the rail; and

Fig. 9 is a top detail of the bushing shown in Fig. 8.

Referring in detail to the embodiment of the invention illustrated by way of example in the accompanying drawings, adjoining rails 1 and 2 (shown in horizontal section)

have their ends in close abutment, and are shown connected together by a usual form of joint, such as fish plates 3 and 4 and bolts 5, 6, 7 and 8, passing through the fish plates and the web of the rail. The present invention may be employed with other forms of rails and conductors as well.

In accordance with certain features of the invention cooperating bonding members are provided which are easily and rapidly assembled, without soldering or welding, which have high efficiency contact, and which are easily and quickly removable as well as having other advantages. As embodied, bonding members preferably of high conductivity connect adjacent rails and are pressed thereagainst with great pressure.

The bonding members also are preferably unattached, effecting their electrical connecting function by contact and pressure, and preferably each bond comprises a plurality of members of high conductivity, separate from but engaging each other by contact and under great pressure, preferably by screw-threaded pressure devices, to form an efficient electrical connection.

Referring in detail to said embodiment, it comprises a rod or like connection of copper or other high conduction metal and in contact therewith a bushing, also preferably of high conduction material, passing through each rail and a bolt passing through each bushing.

The rod or wire 12 is of sufficient thickness and hardness to stand great pressure without shearing, and each bushing 20 is shaped at its contacting end preferably to have extended and close contact with the rod. Also as embodied and in accordance with certain features of the invention, the rod is supported by the bolts, the bolts passing through the bushings in the rails.

In accordance with one feature of the invention also, a pressure member is provided having a dentated, that is, a multi-toothed or multi-pointed surface, which is pressed firmly against the rail and having also an extended surface in pressure contact with some part of the high conduction bond, thereby insuring good and efficient and permanent electrical contact at all joints.

These various features of the invention, together with others not yet referred to but later to be pointed out herein, may all be used together in combination, or certain of

said features may be employed without the others.

Referring now in detail to the construction of the embodiment illustrated by way of example in the accompanying drawings, an inter-rail bond member 12 is provided, preferably of some high conduction metal such as copper, and this inter-rail bond member is likewise preferably of such size and 10 hardness as to satisfactorily meet all service conditions, such for example as minimum electrical resistance and strength to resist shearing under pressure. The inter-rail bond or rod 12 has suitable connection to 15 the rails at either end, and in the present preferred embodiment it passes through an orifice 13, in an enlargement 14 formed on a bolt 16 just beneath the head 15 thereof. Bolt 16 passes through a hole in the web 17 20 of the track rail, or other electrical conducting rail or like member. The device as further described is employed at each end of the bond 12, but a single description will suffice for both devices.

25 As previously stated, and in accordance with one feature of the invention, it is preferred to bring the high conduction metal bond into direct contact with the rail, and this is preferably effected by employing in 30 addition a bushing 20, of copper or other suitable metal, the bushing encircling the bolt 16 and having a relatively extended surface in engagement with the bond or rod 12. The rod 12 and bushings 20 are preferably 35 separate but are subjected to great pressure contact with reference to each other to insure low resistance and efficient conductivity. This construction also conduces to economy in replacing, as the entire device 40 may be disassociated and reassembled without being destroyed, or the parts thereof in any wise distorted or impaired. In the embodied form of the bushing 20, it has a hollow cylindrical stem part 21 encircling 45 the bolt 16 and passing through the rail. Bushing 20 is provided with two laterally and oppositely extending wings 22 and 23, which on their outer surfaces are shaped to conform to the bond 12. The bond 12 is 50 shown herein of cylindrical form, and the wings 22 and 23 are correspondingly internally shaped, to receive and press closely and firmly against the cylindrical rod 12 for a considerable distance therealong at either 55 side of the bolt 16.

In accordance with one feature of the invention, as already indicated, and as at present preferred, a pressure block or member 26 is provided for supporting or backing the 60 wings 22 and 23 of the bushing 20 and serving to press them firmly throughout their length against a rod 12. For this purpose the corresponding surface 27 of the pressure member 26 has recesses 28 and 29 formed therein of a shape or configuration conforming close-

ly or intimately to the back faces of the wings 22 or 23, so that the wings may lie in the recesses, be firmly and adequately supported thereby, and be firmly pressed against the rod 12. The present preferred shape of 70 the wings and of the corresponding recesses in the block will be seen from Figs. 1, 6, 8 and 9.

The wings 22 and 23 of bushing 20, and the corresponding seats therefor in the pressure block 26 are preferably curved downwardly toward the bushing (as will be seen from Figs. 1 and 8) and the underside of the bolt head 15 is similarly cylindrically grooved in a corresponding longitudinal 80 curve to fit closely the top of the cylindrical rod 12 as shown at 11. This permits a curving or flexure of rod 12 under the pressure of the bolt, thereby rendering more close and extensive conducting contact between the 85 various conducting members.

To further insure or increase the contact surface of the entire device, the opposite face of the block 26, that is, the surface thereof which is in engagement with the track rail or the like is dentated, that is, it is provided with a large number of teeth or sharp points which are pressed against the surface of the rail by the bolt pressure, and which are possibly more or less upset 90 thereagainst, thereby insuring close and permanent contact despite unevenness in the surface of the rail, and which also act as a preventive to the encroachments or interpolation of rust. This dentated surface will be 95 clear from Figs. 1, 2 and 5. Thus there is likewise provided close, firm and efficient electrical contact from the rod 12 through the bushing wings 22 and 23, and the pressure block 26, to the rails 1 and 2.

To insure the bolt 16 being screwed up tight while exerting powerful pressure upon the parts already described, the side 27 of block 26 is cut away at 33 to receive the enlargement 14 of the bolt with sufficient clearance that the pressure of the bolt head will come directly upon the bond 12, the bushing 20 and the pressure block 26. The nut 30 is screwed on bolt 16 and a spring washer 31 or other locking means may be provided.

The block 26 is also shaped to fit snugly beneath or against the under side of the ball or tread of the rail and at the same time to fit snugly over the upper part or surface of the flange of the rail, as is best shown in Fig. 2, and is thereby wedged or fastened against any turning movement. The bond is thereby insured or fortified against loosening from any movement of the track, or relative movement of the abutting rail ends due to vibration, or to loose joints, or from other causes, as there can be no turning or loosening or shearing movement of the bond mechanism with the relative movement of the rail ends, due to this close-fitting or

wedged in position of the respective blocks 26 with both the rails at and adjacent to their joint.

By the construction described, any shearing 5 of the bond or high conduction elements or constituents thereof from the screwing down or tightening of nut 30, or otherwise is prevented. By screwing up the nut only a crushing strain from both sides is put on rod 10 12 and the wings or flanges 22 and 23 of bushing 20, thereby increasing or improving the contact without danger of disarranging or disrupting the parts. These advantages are gained while preserving the ease and 15 rapidity of dis-assembling, together with preservation of the bond intact and uninjured for reassembling.

The invention in its broader aspects is not limited to the details of construction and 20 arrangement shown and described, but changes may be made therein within the scope of the accompanying claims without departing from the principles of the invention and without sacrificing its chief ad- 25 vantages.

What I claim is:—

1. In combination with abutting rail ends having bolt holes therein, an electric track bond comprising bolts apertured just beneath their heads and a rail connecting electrically conductive rod passing through the apertures in the bolt heads and bushings surrounding the bolts within the rails and having flared protruding ends partly encircling said rod.

2. In combination with abutting track rail ends having bolt apertures therethrough, of the bolts passing through the apertures, a bushing of highly conductive material about each bolt and within the aperture and having an enlarged laterally extending end, a member interposed between said end and the side of the rail, the bolt head pressing said enlarged end against said member and said member against the rail, and a bond of highly conductive metal connecting the bolts and pressed by the bolt into close contact with said enlarged end.

3. In combination with abutting track rail ends having bolt apertures therethrough, of the bolts passing through the apertures, a bushing of highly conductive material about each bolt and within the aperture and having an enlarged laterally extending end, a member interposed between said end and the side of the rail and having points pressing closely against the rail, the bolt head pressing said enlarged end against said member and said member against the rail, and a bond of highly conductive metal connecting the bolts and pressed by the bolt into close contact with said enlarged end.

4. In combination with abutting track rail ends having bolt apertures therethrough, of the bolts passing through the apertures,

a bushing of highly conductive material about each bolt and within the aperture and having an enlarged laterally extending end, a member shaped on its exterior face to receive the enlarged end of the bushing interposed between said end and the side of the rail, the bolt head pressing said enlarged end against said member and said member against the rail, and a bond of highly conductive metal connecting the bolts and pressed by the bolt into close contact with said enlarged end.

5. In combination with abutting track rail ends having bolt apertures therethrough, of the bolts passing through the apertures, a bushing of highly conductive material about each bolt and within the aperture and having an open, flared end, a member interposed between said end and the rail, the bolt head pressing said open, flared end against said member and said member against the rail, and a bond of highly conductive metal connecting the bolts and pressed by the bolt into close contact with said open, flared end.

6. In combination with abutting track rail ends having bolt apertures therethrough, of the bolts passing through the apertures, a bushing of highly conductive material about each bolt and within the aperture and having an open, flared end, a member shaped on its exterior face to receive the open, flared end of the bushing interposed between said end and the rail, the bolt head pressing said open, flared end against said member and said member against the rail, and a bond of highly conductive metal connecting the bolts and pressed by the bolt into close contact with said open, flared end.

7. In combination with abutting track rail ends having bolt apertures therethrough, of the bolts passing through the apertures, the bolts having holes therethrough closely adjacent to their heads, a bushing of highly conductive material about each bolt and within the aperture and having an enlarged laterally extending end, a member interposed between said end and the side of the rail, the bolt head pressing said enlarged end against said member and said member against the side of the rail, and a bond of highly conductive metal passing through the holes in the bolts, connecting the bolts and pressed by the bolt into close contact with said enlarged end.

8. In combination with abutting track rail ends having bolt apertures therethrough, of the bolts passing through the apertures, the bolts having holes therethrough closely adjacent to their heads, a bushing of highly conductive material about each bolt and within the aperture and having an enlarged laterally extending end, a member shaped on its exterior face to receive the enlarged end of the bushing interposed between said end and the side of the rail, the bolt head

- pressing said enlarged end against said member and said member against the side of the rail, and a bond of highly conductive metal passing through the holes in the bolts, connecting the bolts and pressed by the bolt into close contact with said enlarged end.
9. In combination with abutting track rail ends having bolt apertures there-through, of the bolts passing through the apertures, the bolts having holes there-through closely adjacent to their heads, a bushing of highly conductive material about each bolt and within the aperture and having an open, flared end, a member interposed between said end and the rail, the bolt head pressing said open, flared end against said member and said member against the rail, and a bond of highly conductive metal passing through the holes in the bolts, connecting the bolts and pressed by the bolt into close contact with said open, flared end.
10. A rail bond comprising in combination a bolt with an apertured head, a bushing surrounding the bolt and provided with laterally and oppositely extending arms, a rod passing through the aperture in the bolt head and bearing against said arms, said bolt extending out over said arms, and a nut for drawing the rod into intimate contact with the bolt head and the said arms.
11. A rail bond comprising in combination a bolt with an apertured head, a pressure block arranged around the bolt and between the head of the bolt and the rail, having a dentated face bearing against the side of the rail, a rod of highly conductive material passing through the aperture in the bolt head, and a nut for the bolt bearing against the opposite side of the rail, for pressing the rod into intimate contact with the bolt head and with the pressure block, and for pressing the dentated face of the pressure block into biting contact with the side of the rail.
12. A rail bond comprising in combination a bolt with an apertured head, a pressure block arranged between the head of the bolt and the side of the rail, a bushing surrounding the bolt and having laterally extending arms resting on the pressure block, a rod of highly conductive metal passing through the aperture in the bolt head and bearing against said arms, and a nut bearing against the other side of the rail for pressing the rod into intimate contact with the bolt head and said arms, and for pressing the pressure block into intimate contact with the rod and with the side of the rail.
13. A rail bond comprising in combination a bolt with an apertured head, a pressure block arranged around the bolt and having a dentated face bearing against the side of the rail, a bushing around the bolt, and provided with laterally extending arms extending over the pressure block, a rod of highly conductive metal passing through the aperture in the bolt head and bearing on said arms, and a nut bearing against the other side of the rail for pressing the rod into intimate contact with the bolt head and said arms, and for pressing the pressure block into intimate contact with said arms and its dentated face into biting contact with the side of the rail.

In testimony whereof, I have signed my name to this specification.

GEORGE W. CONRAD.
